Patented Jan. 23, 1912.

UNITED STATES PATENT OFFICE.

EDWARD W. MURPHY, OF BRIDGEPORT, CONNECTICUT.

TRUCK ATTACHMENT FOR CARRYING BEEF.

1,015,393.

Specification of Letters Patent.

Patented Jan. 23, 1912.

Application filed July 3, 1911. Serial No. 636,752.

To all whom it may concern:

Be it known that I, EDWARD W. MURPHY, a citizen of the United States, residing at Bridgeport, county of Fairfield, State of Connecticut, have invented an Improvement 5 in Truck Attachments for Carrying Beef, of which the following is a specification.

This invention has for its object to provide a truck for lifting and carrying heavy 10 articles, more particularly for handling beef and other large meat, and especially to provide an attachment for ordinary hand trucks whereby any truck may be adapted to the purpose in question.

15 In unloading beef and the like from cars and in moving the same in storage warehouses and elsewhere it has heretofore been necessary to lift the carcasses or sides from the hooks on which the same are hung and 20 deposit them upon a truck for purposes of transportation, thereby imposing considerable labor upon the porters or warehousemen which it is the object of the present invention to eliminate by providing a truck by 25 which the lifting operation may be performed by means of the truck itself.

These and other objects of the invention, together with means whereby the same may be carried into effect, will best be understood 30 from the following description of certain forms or embodiments thereof illustrated in the accompanying drawings. It will be understood however that the constructions described and shown have been chosen for illustrative purposes merely and that the invention may be embodied in other forms without departing from the spirit and scope 35 thereof.

In said drawings: Figure 1 is a side view, 40 partly broken away, of a truck having my attachment applied thereto. Fig. 2 is a detail view, partly in longitudinal section and on an enlarged scale, of the adjusting means for the lifting arm, showing a slightly modified 45 construction. Fig. 3 is an elevation at right angles to Fig. 1 of the attachment removed from the truck. Figs. 4 and 5 are respectively a side view and a plan of the lifting hook used in connection with the truck attachment. Fig. 6 is a plan view of certain 50 parts shown in Fig. 1.

10 denotes the body or frame of a truck of ordinary or well-known form provided at its upper end with handles 11 and mounted 55 at its lower end upon wheels 12 beyond which is the usual nose 13, ordinarily in the

form of an iron plate or extension projecting at an angle to the frame.

14 denotes brackets secured to the nose 13 by means of bolts 29 and supporting a rod 60 or elongated bolt 15 upon which is pivoted the lifting arm of the present attachment. It will be obvious that the two brackets 14 may, if desired, be integrally connected or that otherwise a single bracket may be employed in place of the two brackets shown for pivotally supporting the lifting arm. Said arm normally projects upwardly, preferably at an acute angle to the truck body, and terminates in a lifting finger 21 having 65 slightly below its end a fixed collar or flange 34.

As shown in Figs. 1 and 3, the lifting arm comprises outer and inner telescoping tubular members 16 and 17 respectively. By 70 sliding said members in and out upon one another the length of the lifting arm may be adjusted. The members are held in adjusted position by means of a pin or bolt 20 which passes through openings 19 in the 75 outer member 16 and may be passed through any desired pair of a series of openings 18 in the inner member 17. In this form of the invention the lifting finger 21 is carried by or formed integral with the inner member 80 85 17.

In Fig. 2 of the drawing is illustrated a slightly modified construction of lifting arm, the same comprising outer and inner telescoping members 22 and 23 respectively. 90 25 denotes a resilient plate secured to the lower end of the outer member 22, as by screws 27, and terminating at its lower end in a locking pin 26 adapted to enter any one of a series of openings 24 in said member 23. 95

30 denotes a collar fixed on the lifting arm, as by clamping the same therearound, to which collar is pivoted, as at 31 a rod 32 which passes loosely through a cap 33 on a tube 40 which is pivoted on a rod 42 suitably 100 secured, as by nuts 44 (see Fig. 6), in openings in the truck handles 11. The end of the rod 32 within the tube 40 is threaded and is provided with a nut 41 engaging the inner face of the cap 33 when the parts are 105 in the position shown in full lines in Fig. 1. By adjusting the nut 41 upon the rod 32 the normal angle of the lifting arm to the truck body may be varied.

43 denotes a cushioning block of rubber 110 or the like within the tube 40 and adapted to receive the end of the rod 32 when the

parts are in the position shown in dotted lines in Fig. 1, said rod 32 at this time telescoping within the tube 40.

28 denotes a hook having a neck 35 terminating in a head 36. 37 denotes a strap or collar swiveled on said neck 35 and to which is pivoted at 38 an eye 39.

The operation of the device is as follows: If it be desired to move a carcass or side of meat suspended in the usual manner upon a hook in a car, warehouse or elsewhere, the hook 28 is engaged with the meat at some suitable point at a convenient distance from the floor or ground, the truck is brought up in substantially the position shown in Fig. 1, the lifting finger 21 is engaged with the eye 39, and the truck swung backwardly by means of its handles 11 upon the wheels 12 as a fulcrum. This causes the lifting arm to be raised and by the engagement of the lifting finger 21 and its collar 34 with the eye 39 causes the meat to be lifted from its suspending hook. Thereafter the lifting arm may be swung backwardly upon its pivot 15 thereby permitting the weight of the meat to rest upon the truck body.

It will be observed that the attachment may be readily applied to any truck merely by drilling the necessary holes in the nose 13 of said truck for the reception of the bolts 29 for attaching the bracket 14 and by boring suitable holes in the handles 11 for the rod 42. It will also be seen that when it is desired to use the truck for any other purpose, the attachment may be readily removed by the removal of the bolts 29 and rod 42.

Having thus described my invention I claim:

40 1. The combination with a truck comprising a body provided at its upper end with handles and at its lower end with wheels, of a lifting arm pivoted to said body near the lower end thereof and projecting upwardly therefrom, and a pair of telescoping members connecting said arm and body.

2. The combination with a truck comprising a body provided at its upper end with handles and at its lower end with 50 wheels, of a lifting arm pivoted to said body near the lower end thereof and projecting upwardly therefrom, a rod pivoted to said arm, a tube carried by said body and having a cap through which said rod passes, and a 55 nut on said rod within said cap.

3. The combination with a truck comprising a body provided at its upper end with handles and at its lower end with 60 wheels, of a lifting arm carried by said body near the lower end thereof and projecting

upwardly therefrom, and a hook for engaging the object to be lifted and provided with means for loose engagement with said arm.

4. The combination with a truck comprising a body provided at its upper end with handles and at its lower end with 65 wheels, of a lifting arm carried by said body near the lower end thereof and projecting upwardly therefrom, a lifting finger at the upper end of said arm provided with a 70 fixed collar, and a hook coöperating with said finger.

5. The combination with a truck comprising a body provided at its upper end with handles and at its lower end with 75 wheels, of a lifting arm carried by said body near the lower end thereof and projecting upwardly therefrom, a hook having a neck, a collar swiveled on said neck, and an eye pivoted to said collar and coöperating 80 with said arm.

6. The combination with a truck comprising a body provided at its upper end with handles and at its lower end with 85 wheels, of a lifting arm carried by said body near the lower end thereof and projecting upwardly therefrom, a lifting finger at the upper end of said arm provided with a fixed collar, a hook having a neck, a collar swiveled on said neck, and an eye pivoted to said 90 collar and coöperating with said finger.

7. A lifting attachment for trucks comprising a bracket, means for detachably securing said bracket to the nose of a truck, and a lifting arm pivoted to said bracket. 95

8. The combination with a truck comprising a body provided at its upper end with handles and at its lower end with 100 wheels, of a lifting arm pivoted to said body near the lower end thereof and projecting upwardly therefrom, a pair of telescoping members connecting said arm and body, and means for relatively adjusting said members.

9. The combination with a truck comprising a body provided at its upper end with handles and at its lower end with 105 wheels, of a lifting arm pivoted to said body near the lower end thereof and projecting upwardly therefrom, a pair of telescoping members connecting said arm and body and means for cushioning said members. 110

In testimony whereof I affix my signature in presence of two witnesses.

EDWARD W. MURPHY.
